Siggett & Siggett

ATTORNEY.

UNITED STATES PATENT OFFICE.

ISAIAH G. HATCHER, OF CHICAGO, ILLINOIS, ASSIGNOR TO THE CLEVELAND BURIAL CASE COMPANY, OF CLEVELAND, OHIO.

DESIGN FOR A PEDESTAL FOR BURIAL-CASKETS.

SPECIFICATION forming part of Design No. 18,859, dated January 15, 1889.

Application filed November 26, 1888. Serial No. 291,912. Term of patent 7 years.

To all whom it may concern:

Be it known that I, ISAIAH G. HATCHER, a citizen of the United States of America, residing at Chicago, in the county of Cook and State of Illinois, have invented and produced a new and original Design for a Pedestal for Burial-Caskets, of which the following is a specification, reference being had to the accompanying drawing, forming part thereof.

10 The figure is a side elevation.

The pedestal is in the form of a column, as shown, having a base, shaft, and capital; but what is considered the novel feature pertains to the shaft, and consists in the spiral molding or beading *a* along the central section of the shaft and cylindrical beading above and below the spiral beading.

What I claim is—

The design for a pedestal or support for a burial-casket herein shown and described, 20 the same being in the form of a column and having spiral beading along the central section of the shaft and a series of cylindrical beads above and below the spiral beading, substantially as set forth. 25

In testimony whereof I sign this specification, in the presence of two witnesses, this 19th day of October, 1888.

ISAIAH G. HATCHER.

Witnesses:

C. L. KING,
C. B. MITCHELL.
